United States Patent Office

Des. 194,719
Patented Feb. 26, 1963

194,719

MOTION PICTURE REEL OR SIMILAR ARTICLE

Eugene Martinez, Irvington on Hudson, and Marvin Kapilow, Croton on Hudson, N.Y., assignors, by direct and mesne assignments, to Reelco Inc., Irvington on Hudson, N.Y., a corporation of New York

Filed Dec. 18, 1961, Ser. No. 67,950

Term of patent 14 years

(Cl. D61—1)

FIG. 1

FIG. 2

FIG. 4

FIG. 1 is a front perspective view of a motion picture reel or similar article, showing our new design.

FIG. 2 is a rear elevational view thereof;

FIG. 3 is a right-side elevational view thereof; and

FIG. 4 is an enlarged, fragmentary perspective view of the rear-center area thereof.

Portions of FIGURE 1 are stippled to indicate contrast.

We claim:

The ornamental design for a motion picture reel or similar article, substantially as shown and described.
